UNITED STATES PATENT OFFICE.

WILLIAM FREDERICK ROBERT MIST, OF TONBRIDGE, ENGLAND.

ROTARY ENGINE.

SPECIFICATION forming part of Letters Patent No. 777,384, dated December 13, 1904.

Application filed October 27, 1903. Serial No. 178,794. (No model.)

To all whom it may concern:

Be it known that I, WILLIAM FREDERICK ROBERT MIST, a subject of the King of Great Britain and Ireland, residing at 97 Barden 5 road, Tonbridge, in the county of Kent, England, have invented certain new and useful Improvements in Rotary Engines; and I do hereby declare the following to be a full, clear, and exact description of the invention, such as 10 will enable others skilled in the art to which it appertains to make and use the same.

My invention relates to improvements in rotary engines, which I will now describe with reference to the drawings accompanying 15 this specification, in which—

Figure 1 shows an elevation of rotary engine constructed according to my invention. Fig. 2 shows a plan of same. Fig. 3 shows an end elevation looking in the direction of the arrow 20 A, Fig. 1. Fig. 4 shows another end elevation looking in the direction of the arrow B, Fig. 1. Fig. 5 shows a vertical section of Fig. 1. Fig. 6 shows an end elevation of the cylinder with a fin cast therewith and also 25 showing a fin permanently fixed to the tubular shaft drawn to a larger scale. Fig. 7 shows a vertical section of same; Fig. 8, an end elevation of cover with steam and exhaust chest removed. Fig. 9 shows an elevation of 30 ratchet-wheel, showing the two cams for operating the valve-rods drawn to a larger scale; Fig. 10, a plan of same. Fig. 11 shows an elevation of the steam-chest drawn to a larger scale. Fig. 12 shows a sectional plan of same. 35 Fig. 13 shows an oblique section taken through the line C D, Fig. 4. Figs. 14 to 20, inclusive, show various views, drawn to a larger scale, hereinafter referred to.

The same characters of reference denote the 40 same parts in all the views.

a, Figs. 5 and 6, shows a revolving cylinder fitted with an internal vane or piston *b*. Such piston is made to fit steam-tight on the tubular shaft *c*, Fig. 2. The method of fitting same steam-tight is as follows: The lower part of the piston is in the form of a sleeve, into which takes a piece of metal *d*, cut to correspond with sleeve, and a spring *e*, placed within a groove, causes the said piece to be 45 pressed down when fitted into sleeve. On

each side of fin, working against cover-plate, is a piece of metal *d'*, fitted to form a lap. On the outer face of cylinder is a projection *f*, Fig. 7, or tubular shaft corresponding in size to the tubular shaft *c*. Through this (and 55 the tubular shaft *c*) passes the solid shaft *g*. In the projection *f* is a shoulder *f'*. The outer edge of the cylinder is flanged (at *h*, Fig. 5) where it revolves within the cover *i*. A balance-weight *i'*, Figs. 6 and 7, is fixed on 60 outside of cylinder to counterbalance the fin *b* inside. In the cylinder works tubular shaft *c* over solid shaft *g*. On the shaft *c* is fitted another vane or piston, *j*, Fig. 6, of such length that it fits the inside of cylinder *a*. 65 The method of keeping this piston steam-tight against inner part of cylinder *a* is as follows: The piston *j* is provided with a sleeve or recess within it. The upper part *l* of the piston is cut to fit this sleeve, and to this part 70 is fitted a spring *m*, which when fitted within sleeve keeps flange *l* close up to cylinder *a*. This flange *l* is made of suitable size to form a lap. Side packing-pieces *p* (see Fig. 15) are fitted each side of fin *j*, and these are pressed 75 outward by springs *p*, fitted in recesses *q*.

Within tubular shafts *c* *d*' and *f* runs solid shafting *g*, Fig. 1.

The flanged edge *h* of revolving cylinder *a*, Fig. 5, revolves in and works against a cover 8 or plate *i*, Fig. 1, fitted to the support *n*. Behind this cover and fitting upon support *n* is fitted the steam and exhaust chest *o*. In the cover are cut ports communicating and corresponding with steam and exhaust ports 85 in steam and exhaust chest.

The steam-jacket *s*, Fig. 1, is bolted to flange of cover *i*. The steam-jacket is larger in diameter near its flange *t* to permit the disk *u*, attached to revolving cylinder *a*, (carrying the cams *v* *w*, working expansion-valves,) to revolve in. The outer end of steam-jacket is bored to size of adjusting-cone *x*, (shown more clearly at Fig. 14,) which on its inner face is grooved and fitted with ball-bearings, working on end of cylinder *a*. This adjusting-cone *x* fits over projecting shaft *f* of cylinder *a* and screws into thread of steam-jacket *s*. When adjusted, the locking-nut *y* retains the adjustment.

Within the supports z 1 2 3 revolve the ratchet-wheels 4, 5, 6, and 7, mounted on a tubular shaft c' , corresponding with shaft c and coupled on their respective sides to sleeve f of cylinder a and end of shaft c , Fig. 5. The ratchet-wheels 5 6 are notched for direct driving and are fitted with pawls 9 10 for the purpose, and the ratchet-wheels 4 and 7 are also notched for reverse driving and are fitted with pawls 8 and 11. Pawls 9 and 10 on ratchet-wheels 5 and 6 are to receive back pressure when engine is driven direct. Pawls 8 and 11 on ratchet-wheels 4 and 7 are to receive back pressure when engine is driven reversed. Free wheels 12 and 13 are connected by the bars 14, which inside the free wheels form sliding bolts working within the ratchet-wheels 4 and 5. Attached to ratchet-wheel 7 is a small wheel 7' with a counterbalance-weight cast on it, Figs. 1 and 2, to counterbalance the fin j . The free wheels 15 and 16 are connected in a similar manner by the bars 17 and form sliding bolts working within ratchet-wheels 6 and 7. The collars 18 are attached to solid shaft g and are fitted with clutch-holes 19 to take clutches 20, (one of which is shown,) fitted on inner cone of free wheels 12, 13, 15, and 16. To throw the free wheels in and out of gear, any known clutch may be employed. The free wheels 13 and 16 are for direct driving. The free wheels 12 and 15 are for driving reverse. The free wheels are only connected to solid shaft when clutched in collars 18. 21 represents couplings for tubular shafts c , c' , and f . (Shown enlarged at Fig. 14.)

Fitted to the outer edge of cylinder a behind its flange h and revolving in the raised portion of steam-jacket s is a flange u , Figs. 5 and 13. To the outer circumference of this is fitted a cam-plate w at a suitable angle, on which takes the jumper-rod 23 in direct driving. On the inner circumference is another cam, v , also at a suitable angle, on which takes the jumper 22 for reverse driving. On the inner side of ratchet-wheel 6 are cams 39 and 40, (see Figs. 9, 10, and 13,) fitted at suitable angles and used for a similar purpose. The rod 26 connects the rods 23 and 24. On the end of rod 24 and within the steam-chest 39' is fitted a slide 27, which is made to move over steam-port 41 when the cams take on rollers. When the cams pass rollers, a spring 29 outside steam-chest withdraws the plug or slide from steam-ports. Rods 22 and 24' work slide 28. Rods 23 and 24 work slide 27.

Exhaust-pipes 30 and 31 are fitted on either side of exhaust-chambers and are so arranged that when port 33 is open port 32 is closed. (See Fig. 8.) Port 32 is open in direct driving and port 33 is closed. Port 33 is open in reverse driving and port 32 is closed. The steam-ports 55 and 56 are so arranged that port 55 is open in direct driving and port 56 closed. The positions are reversed in revers-

ing the engine. The position of steam and exhaust ports as here shown is as follows: The stationary piston is between steam-ports. When the moving piston after the revolution comes in contact with the other piston, simultaneously the lap of this moving piston must just open exhaust. 70

38, Fig. 1, is a pulley-wheel. The method of working the wheel is as follows, assuming the steam-port 55 to be open and port 56 closed, Fig. 8, and this exhaust-port 32 open and port 33 closed, and the pawls 8 and 11 on ratchet-wheels 4 and 7 to be clear of the notches, the direct-driving free wheels 13 and 16 are in gear and 12 and 15 out of gear, the 80 piston b , attached to revolving cylinder a , Fig. 6, to be in position between ports 55 56, and the piston j , Fig. 3, attached to tubular shaft c , to be in the position shown by arrow A, Fig. 6: When steam is admitted through 85 port 55, the piston is held in position by pawl on ratchet-wheel 5, Fig. 1. The other piston, j , is driven round, taking with it the tubular shaft c , also the free wheels 16 and 15. The wheel 16 (by means of the clutch in collar 18, 90 Fig. 1) also rotates the shaft g and pulley-wheel 38. When the piston j arrives at the position, say, B, (denoted by arrow at Fig. 6,) the roller on jumper 24 takes cam 39 of ratchet-wheel 6 and moves slide 27 over port 41, shutting off steam from port 55, Fig. 8. The revolution is completed by expansion of steam already within cylinder a . When the piston j engages against the piston b , the lap of flange l of piston j just opens exhaust-port 32, Fig. 8, 100 the exhaust at this point not being full. The impetus of piston j (working in conjunction with tendency of steam to obtain a larger exhaust) drives the piston b over steam-port 55, in which position it will be seen the lap or 105 flange l on piston j gives a full exhaust. The cam then releases roller, steam again enters port 55, piston j is held in position by pawl 10, and piston b in its turn is driven round. On arriving again at point B, Fig. 6, steam 110 is shut off again by means of cam w on cylinder a taking roller on rod 23 and moving slide 27 back again. This is relieved again, as in the former revolution, when piston b has driven piston j past steam-port 55. During 115 the revolution of piston b the ratchet-wheels 4 and 5 are driven round, (through couplings 21, see Fig. 14) taking with them free wheels 12 and 13. The free wheel 13 engages with the clutch of collar 18, and thus a continuous 120 motion of shaft and pulley-wheel 38 is obtained.

With reference to Figs. 11 and 12, the steam-chest 39' has two ports 40' and 41 cut in its outer faces 42 and 43, respectively, and so 125 cut that when port 40' is open port 41 is closed, and vice versa. Formed in one with steam-chest 39' are two expansion valve-chests 44, in which work the expansion-rods 24' and 24. Springs 47 and 48 act on the inside face 130

of expansion valve-chest 44 and on the expansion-rods 24' and 24, respectively. Within the steam-chest 39' move two plugs or slides 49 and 50, which are connected to rod 51 by 5 helical springs 52 and 53. Mounted on the outside end of rod 51 is a hand-wheel 54, which operates the slides 49 and 50 backward or forward, as the case may be. Over ports 40' and 41 slide the rods 24' and 24. A steam- 10 pipe 57 enters the steam-chest 39' for conveyance of steam into the same. The action is as follows: Steam is admitted to steam-chest 39' through pipe 57 and in this position escapes through the port 41 into expansion valve-chests 44 and thence to cylinder through port 55. The expansion-rods are operated upon by 15 their respective cams, already described, and work in separate chambers 44 along the face of the steam-chest, closing ports 40' and 41 20 as required. By this means when the slide-valves are forced over ports 40' and 41 the only pressure on rollers and cams is that caused by compression of the springs. The position of steam and exhaust ports with the steam-chest is as follows: Assuming the stationary 25 piston to be perpendicular, the steam-ports 55 and 56 are cut in cover-plate, one on either side of it and close to said piston. The position for exhaust-ports is as follows: After 30 the moving piston has completed a revolution it comes in contact with the stationary piston and the end of the moving piston or lap will simultaneously open exhaust-port.

With reference to Figs. 17, 18, and 19, *i* is 35 the cover-plate with the steam and exhaust chest removed in order to show an alternative arrangement of cover-plate and different-pattern steam-chest provided with separate cylinders to facilitate the main piston passing 40 the perpendicular. 55 and 56 are two steam-ports corresponding to those heretofore described. 32 and 33 are two exhaust-ports cut in cover leading from cylinder *a*, and 58 and 59 are the final exhaust-pipes, as hereinafter 45 described. A small cylinder 60 is suitably attached to the outside of cover-plate *i*, in which slide two pistons 61 and 62, which are connected by a helical or other spring 63. On pistons 61 and 62 are cast or otherwise 50 permanently fixed two smaller cylinders 64 and 65, respectively, in which slide two pistons 66 and 67, (shown at Figs. 19 and 20,) and attached to each of these are bolts or 55 rods 68 and 69, which slide in groove 70, cut in cylinder 60 and cover-plate *i*, respectively. Steam is introduced into the small cylinders 64 and 65 through the inlet 72 and 73. The exhaust cut-off covers the position 60 designated by numeral 74 on steam-cover and leaves slide 70 clear on the inner side and 68 and 69 clear of the outside. With reference 65 to Fig. 18, *b* and *j* are two fins or pistons heretofore referred to, which have recesses 75, 76, 77, and 78 cut on their exterior top ends.

The mode of operation is as follows: As-

suming piston *b* to be in position between ports 55 and 56 and piston *j* has completed nearly a revolution, such piston comes in contact with piston *b*, opens exhaust 70 32. The recess 78 is opposite cylinder 64. The exhausting steam enters at 72, Fig. 19, and drives rod or bolt 68 into recess 78. The piston 61 in the cylinder 60 now moves back toward the exhaust-port 58, taking with it bolt or rod 68, as this in being engaged in recess 75 78 takes the main piston *j* with it and drives *b* before it. The slide 71 moves also, and thus keeping the parts steam-tight. When piston 61 passes final exhaust-pipe 58, the piston *j* is then in position and piston *b* is 80 past steam-port and exhausts the steam, thus releasing pressure behind bolt or rod 68 and is withdrawn by a spring. The piston 61 returns to its former position by spring 63. The slide 71 is also moved back by spring 79, 85 Fig. 17, or by a projection on the pistons 61 or 62, which when returning takes slide 71 with it. When it is required to reverse the engine, piston 62 is used, when port 33 is open and precisely the same action takes place. Cylinder 65 and piston 62 acting now, owing to port being open and 32 closed, causes cylinder 64 and piston 61 to be out of action.

What I claim as my invention, and desire to 90 secure by Letters Patent, is—

1. In a rotary engine, a driving-shaft, a hollow shaft and a cylinder mounted thereon, mechanism for operatively connecting said driving-shaft with and for disconnecting the same from said hollow shaft and cylinder and 100 means for rotating said hollow shaft and cylinder, substantially as described.

2. In a rotary engine, a driving-shaft, a hollow shaft and a cylinder mounted thereon, mechanism for operatively connecting said driving-shaft with and for disconnecting the same from said hollow shaft and cylinder and 105 means for alternately rotating said hollow shaft and cylinder, substantially as described.

3. In a rotary engine, a driving-shaft, a hollow shaft and a cylinder mounted thereon, mechanism for operatively connecting said driving-shaft with and for disconnecting the same from said hollow shaft and cylinder and a plurality of pistons within said cylinder for 110 rotating said hollow shaft and cylinder, substantially as described.

4. In a rotary engine, a driving-shaft, a hollow shaft and a cylinder mounted thereon, a single mechanism for both operatively connecting said driving-shaft with and for disconnecting the same from said hollow shaft and cylinder, and means for rotating said hollow shaft and cylinder, substantially as described.

5. In a rotary engine, a driving-shaft, a hollow shaft and a cylinder mounted thereon, mechanism for operatively connecting said driving-shaft with and for disconnecting the same from said hollow shaft and cylinder and 130

- a pair of pistons within said cylinder one mounted to rotate said cylinder and one mounted to rotate said hollow shaft, substantially as described.
- 5 6. In a rotary engine, a driving-shaft, a hollow shaft and a cylinder open at one end mounted thereon, a suitable casing for said cylinder provided with inlet and exhaust ports, mechanism for both operatively connecting 70 said driving-shaft with and for disconnecting the same from said hollow shaft and cylinder and a pair of pistons within said cylinder for rotating said hollow shaft and cylinder, substantially as described.
- 10 7. In a rotary engine, a driving-shaft, a hollow shaft and a cylinder open at one end mounted thereon, a suitable casing for said cylinder provided with inlet and exhaust ports, mechanism for both operatively connecting 75 said driving-shaft with and for disconnecting the same from said hollow shaft and cylinder and a pair of pistons within said cylinder for alternately rotating said hollow shaft and cylinder, substantially as described.
- 15 8. In a rotary engine, a driving-shaft, a hollow shaft and a cylinder mounted thereon, clutch mechanism for connecting said driving-shaft with said hollow shaft and cylinder, and means for rotating said hollow shaft and cylinder, substantially as described.
- 20 9. In a rotary engine, a driving-shaft, a hollow shaft and a cylinder mounted thereon, independent clutch mechanisms for connecting said driving-shaft with said hollow shaft and cylinder, and a pair of pistons within said cylinder for alternately rotating said hollow shaft and cylinder, substantially as described.
- 25 10. In a rotary engine, a driving-shaft, a hollow shaft and a cylinder open at one end 80 mounted thereon, a suitable casing for said cylinder provided with inlet and exhaust ports, independent clutch mechanisms for connecting said driving-shaft with said hollow shaft and cylinder, a pair of pistons within said cylinder one mounted to rotate said hollow shaft and one mounted to rotate said cylinder, and means for alternately actuating said pistons, substantially as described.
- 30 11. In a rotary engine, a driving-shaft, a hollow shaft and a cylinder open at one end 85 mounted thereon, a suitable casing for said cylinder provided with inlet and exhaust ports, independent clutch mechanisms for connecting said driving-shaft with said hollow shaft and cylinder, a pair of pistons within said cylinder one mounted to rotate said hollow shaft and one mounted to rotate said cylinder, and a valve mechanism for alternately actuating said pistons, substantially as described.
- 35 12. In a rotary engine, a driving-shaft, a hollow shaft and a cylinder open at one end 90 mounted thereon, a suitable casing for said cylinder provided with inlet and exhaust ports, means for rotating said shaft in one direction and a clutch mechanism in combination with a ratchet and pawl for reversing the direction of rotation, substantially as described.
- 40 13. In a rotary engine, a driving-shaft, a cylinder mounted thereon, a plurality of pistons for said cylinder, operative connections between said shaft and pistons, means for rotating said pistons in one direction and a clutch mechanism in combination with a ratchet and pawl for reversing the direction of rotation, substantially as described.
- 45 14. In a rotary engine, a driving-shaft, a cylinder mounted thereon, a plurality of pistons for said cylinder, operative connections 70 between said shaft and said pistons, a steam-chest adjacent said cylinder provided with ports for direct and reverse driving, a suitable valve-gear for admitting steam through said ports to said pistons, and means for closing either of said ports as may be desired, substantially as described.
- 50 15. In a rotary engine, a driving-shaft, a cylinder mounted thereon, a plurality of pistons for said cylinder, operative connections 75 between said shaft and said pistons, a steam-chest adjacent said cylinder provided with ports for direct and reverse driving, a suitable valve-gear for admitting steam through said ports to said pistons, and hand-operated 80 means for closing either of said ports as may be desired, substantially as described.
- 55 16. In a rotary engine, a driving-shaft, a cylinder mounted thereon, a plurality of pistons for said cylinder, operative connections 85 between said shaft and said pistons, means for rotating said pistons, and means for locking said pistons against back pressure, substantially as described.
- 60 17. In a rotary engine, a driving-shaft, a cylinder mounted thereon, a plurality of pistons for said cylinder, operative connections 90 between said shaft and said pistons, a suitable valve mechanism for rotating said pistons in either direction, and a ratchet and 100 pawl for locking said pistons against back pressure, substantially as described.
- 65 18. In a rotary engine, a driving-shaft, a cylinder mounted thereon, a plurality of pistons for said cylinder, operative connections 105 between said shaft and said pistons, a suitable valve mechanism for rotating said pistons in either direction, and a separate ratchet and pawl for locking each of said pistons against back pressure in either direction of 110 rotation, substantially as described.
- 70 19. In a rotary engine, a driving-shaft, a cylinder mounted thereon, a two-part piston mounted on the inner surface of the cylinder-casing, and means between said parts for 115 making a steam-tight joint at the junction of said piston with said driving-shaft, substantially as described.
- 75 20. In a rotary engine, a driving-shaft, a cylinder mounted thereon, a two-part piston 120 mounted on the inner surface of the cylinder-casing, and a spring between said parts for making a steam-tight joint at the junction of said piston with said driving-shaft, substantially as described.
- 80 130 65 135 60 140 55 145 50 150 45 155 40 160 35 165 30 170 25 175 20 180 15 185 10 190 5 195 0

21. In a rotary engine, a driving-shaft, a hollow shaft and a cylinder mounted thereon, a two-part piston mounted on said hollow shaft within said cylinder, and means between said parts for making a steam-tight joint at the junction of said piston with said cylinder, substantially as described. 5
22. In a rotary engine, a driving-shaft, a hollow shaft and a cylinder mounted thereon, a two-part piston mounted on said hollow shaft within said cylinder, and a spring between said parts for making a steam-tight joint at the junction of said piston with said cylinder, substantially as described. 10
23. In a rotary engine, a driving-shaft, a cylinder mounted thereon, a piston therein formed in two parts, one of said parts provided with a sleeve in which the other of said parts is constructed to fit, and means between said parts for forcing them apart to make a steam-tight joint at the ends of the piston, substantially as described. 15
24. In a rotary engine, a driving-shaft, a cylinder mounted thereon, a piston therein formed in two parts, one of said parts provided with a sleeve in which the other of said parts is constructed to fit, means between said parts for forcing them apart to make a steam-tight joint at the ends of the piston, side packing-pieces and means between said piston and said side pieces for making a steam-tight joint at the sides of the piston, substantially as described. 20
25. In a rotary engine, a driving-shaft, a cylinder mounted to rotate thereon, a steam-chest provided with inlet and exhaust ports to said cylinder, a valve-rod and valve for controlling said inlet-port, a jumper-rod operatively connected to said valve-rod, and means on said cylinder for engaging said jumper-rod and controlling the point of cut-off, substantially as described. 25
26. In a rotary engine, a driving-shaft, a cylinder mounted to rotate thereon, a steam-chest provided with inlet and exhaust ports to said cylinder, a valve-rod and valve for controlling said inlet-port, a jumper-rod operatively connected to said valve-rod, and a cam-surface on said cylinder for engaging said jumper-rod and controlling the point of cut-off, substantially as described. 30
27. In a rotary engine, a driving-shaft, a cylinder mounted to rotate thereon, a steam-chest provided with inlet and exhaust ports to said cylinder, a valve-rod and valve for controlling said inlet-port, a jumper-rod operatively connected to said valve-rod, means for normally keeping said inlet-port uncovered, and means on said cylinder for engaging said jumper-rod and controlling the point of cut-off, substantially as described. 35
28. In a rotary engine, a driving-shaft, a cylinder mounted to rotate thereon, a steam-chest provided with inlet and exhaust ports to said cylinder, a valve-rod and valve for controlling said inlet-port, a jumper-rod operatively connected to said valve-rod, a spring connected to said valve-rod for normally keeping said inlet-port uncovered, and a cam-surface on said cylinder for engaging said jumper-rod and controlling the point of cut-off, substantially as described. 40
29. In a rotary engine, a driving-shaft, a cylinder mounted to rotate thereon, a steam-chest provided with inlet and exhaust ports to said cylinder for both direct and reverse driving, a valve-rod and valve for controlling each of said inlet-ports, jumper-rods operatively connected to said valve-rods, means for normally keeping said inlet-ports uncovered, and means on said cylinder for engaging said jumper-rods and controlling the point of cut-off, substantially as described. 45
30. In a rotary engine, a driving-shaft, a cylinder mounted to rotate thereon, a steam-chest provided with inlet and exhaust ports to said cylinder for both direct and reverse driving, a valve-rod and valve for controlling each of said inlet-ports, jumper-rods operatively connected to said valve-rods, means for normally keeping said inlet-ports uncovered, means on said cylinder for engaging said jumper-rods and controlling the point of cut-off, and means independent of said valves for temporarily covering either of said inlet-ports as may be desired, substantially as described. 50
31. In a rotary engine, a driving-shaft, a cylinder mounted to rotate thereon, a steam-chest provided with inlet and exhaust ports to said cylinder for both direct and reverse driving, a valve-rod and valve for controlling each of said inlet-ports, jumper-rods operatively connected to said valve-rods, springs for normally keeping said inlet-ports uncovered, and cam-surfaces on said cylinder for engaging said jumper-rods and controlling the point of cut-off, substantially as described. 55
32. In a rotary engine, a driving-shaft, a hollow shaft and a cylinder mounted thereon, operative connections between said driving-shaft and said hollow shaft and cylinder, a pair of pistons constructed to rotate said cylinder and said shaft, a steam-chest provided with inlet and exhaust ports to said cylinder, a valve-rod and valve for controlling said inlet-port, a jumper-rod operatively connected to said valve-rod, means for normally keeping said inlet-port uncovered, means on said cylinder for engaging said jumper-rod and controlling the point of cut-off to said cylinder-piston, and means on said hollow shaft for engaging said valve-rod and controlling the point of cut-off to said hollow-shaft piston, substantially as described. 60
33. In a rotary engine, a driving-shaft, a hollow shaft and a cylinder mounted thereon, operative connections between said driving-shaft and said hollow shaft and cylinder, a pair of pistons constructed to rotate said cylinder and said shaft, a steam-chest provided with inlet 65

and exhaust ports to said cylinder, a valve-rod and valve for controlling said inlet-port, a jumper-rod operatively connected to said valve-rod, means for normally keeping said 5 inlet-port uncovered, a cam-surface on said cylinder for engaging said jumper-rod and controlling the point of cut-off to said cylinder-piston, and a cam-surface on said hollow shaft for engaging said valve-rod and controlling the point of cut-off to said hollow- shaft piston, substantially as described.

34. In a rotary engine, a driving-shaft, a cylinder mounted thereon, a suitable casing for said cylinder, means for rotating said cyl- 10 inder, an antifriction-bearing between said

casing and cylinder, and an adjusting-cone for said bearing, substantially as described.

35. In a rotary engine, a driving-shaft, a cylinder mounted thereon, a suitable casing for said cylinder, means for rotating said cyl- 20 inder, an antifriction-bearing between said casing and cylinder, an adjusting-cone for said cylinder, and means for locking said cone in position, substantially as described.

In testimony whereof I affix my signature in 25 presence of two witnesses.

WILLIAM FREDERICK ROBERT MIST.
